H. W. RICHARDSON

HEAT SPILLER FOR INCUBATORS

Filed June 7, 1924

INVENTOR
Henry W. Richardson
BY Thomas L. Miller
ATTORNEY

UNITED STATES PATENT OFFICE.

HENRY W. RICHARDSON, OF LITTLE FALLS, NEW YORK, ASSIGNOR TO PERCY D. PETERS, OF LITTLE FALLS, NEW YORK.

HEAT SPILLER FOR INCUBATORS.

Application filed June 7, 1924. Serial No. 718,666.

To all whom it may concern:

Be it known that I, HENRY W. RICHARDSON, a citizen of the United States, residing at Little Falls, in the county of Herkimer and State of New York, have invented certain new and useful Improvements in Heat Spillers for Incubators, of which the following is a specification, reference being had therein to the accompanying drawing.

10 My invention relates to a heat spiller for incubators, and I declare the following to be a full, clear, concise and exact description thereof sufficient to enable anyone skilled in the art to which it appertains to 15 make and use the same reference being had to the accompanying drawings in which like reference characters refer to like parts throughout the specification.

The object of the invention is to provide 20 an automatic device for opening up a door or vent in the upper part of the compartment of an incubator to the atmosphere, whereby to allow for the escape or spilling of hot air, when the temperature in said 25 compartment rises above a predetermined degree.

The object will be understood by referring to the drawings in which:

30 Fig. 1 is a perspective view of the device, showing the correlated parts of an incubator which is broken away;

Fig. 2 is a detailed enlarged view, showing a perspective of a bracket member employed;

35 Fig. 3 is an enlarged detail view showing a perspective of a wire rod used;

Fig. 4 is a detail view, showing a perspective of the door or spiller and immediate parts;

40 Fig. 5 is a fragmentary view of the door, showing an inside elevation thereof;

Fig. 6 is a detail perspective view of the door frame and door;

45 Fig. 7 is a detail view, showing a modification of the door;

Fig. 8 is a detail view of thermostat used.

Referring more particularly to the drawings, the upper part of the front wall of an incubator is represented by 1. There is 50 shown also a portion of the upper frame 2 to which is attached a fabric 3 forming a partition wall between the compartment adapted to contain the eggs and that containing the pipes, which fabric partition prevents drafts within the incubator. These

parts are well known in the construction of incubators and are mentioned merely to show the relation of those parts to the ones which are novel and embody a metallic door or heat spiller 5 made of sheet metal and having centrally disposed laterally located trunnions 6, 6 formed integral therewith. Trunnions 6, 6 are mounted in bearings 7, 7 made integral with metallic frame 8 that is set in an opening in wall 1 of the incubator, 65 whereby said door 5 is permitted to swing upon its trunnions 6, 6 as pivots. Door 5 is limited to swing with its top part outward by reason of the extended upper portions 10, 10 of frame 2 which will overlap door 5 70 when in closed position and, therefore, prevent said door 5 from swinging therewith.

A bracket 15 is fulcrumed upon a rod 16 that passes through apertures 18, 18 made in the side walls 19, 19 of bracket 15. 75 Bracket 15 is held in horizontal position or at right angles to the surface of door 5 by a depending or bent over part 20 which is adapted to abut against the inner surface of door 5 and, thereby, hold bracket 15 in horizontal position. Rod 16 is bent or offset at 12 to engage apertures 18, 18 formed in side walls 19, 19. The ends 23, 23 of rod 16 are bent into circles to allow for the projection therethrough of screw bolts 24, 24 that are 85 mounted to door 5. Another part 25 of bracket 15 is bent upward to be engaged by the adjusting screw 26 that is screw mounted to head or boss 27. Head 27 is riveted to door 5. By adjusting the outer end of screw 90 26 more or less near part 25, the throw or swing of bracket 15 on its fulcrum, namely rod 16 will be limited in accordance therewith. Door 5 is held normally closed by weight 28 that is mounted on one of the bolts 95 24 aforementioned. Said bolt projects into the center of said weight 28.

The outer or free ends of side walls 19, 19 of bracket 15 are equipped, in each instance, with an aperture to form bearings 100 for the shaft 30 upon which turns an antifriction roller 31 having an annular groove in its peripheral surface.

The free end of rod 40 is adapted to rest against the under surface of antifriction 105 roller 31. The opposite end of rod 40 is held by a set screw 41 in a recess formed in rock member 42. Moreover, rod 40 has an offset portion at 43.

Rock member 42 is fulcrumed upon 110

headed shaft 44 that is equipped with screw threads at one end for mounting nut 44a. Shaft 44 has bearings in upstanding standards 45, 45 that are formed integral with base 46, which is held to cross bar 47 of frame 1 by screws, 48, 48. Wire rod 50 has one end housed in a recess in member 42 and fastened thereto by a set screw 51. A wire or rod 52 having a bent over upper horizontal part 53 extending towards the free end of rod 50 to provide sufficient leverage, projects up through a loose fitting aperture made in rock member 42. The extreme end of rod 52 is bent again downward at right angles and formed into a loop at 54 to engage the horizontal part of rod 50, whereby the vertical movements of rod 52 will be communicated to rod 50 to actuate door 5 to open position. Moreover, horizontal part 53 will exert a yielding pull on thermostat 61 to aid in prolonging the life thereof. The lower part of rod 52 extends down through a hollow tube 55 that is screw mounted to base 46. The extreme lower end of rod 52 passes through a loose fitting aperture made in lever 56. An adjustable thumb nut 57 is screw mounted to said lower end of rod 52, whereby to move the end of lever 56 more or less up and down relative to rod 52 to govern the degree of vertical movement of lever 52. Lever 56 is fulcrumed at 58 to the depending part of arm 59. Arm 59 is fixed to the lower end of hollow tube 55 by a set screw 60.

A thermostat 61 of well known construction is suspended from arm 59. A short shaft 62 fastened to the lower plate 63 of thermostat 61 is adapted to make contact with lever 56, whereby to transfer the expansion of said thermostat 61 to said lever 56. Wire rod 52 that connects lever 56 with rod 50 will exert, because of its horizontal part 53, a yielding pull on thermostat 61, whereby to open door 5 in a steady manner and also be easy and effect less strain on said thermostat 61, whereby to prolong the life thereof. It will be found that a yielding pull such as above described will not be as harmful as a direct pull on thermostat 61, for a direct pull will cause the thermostat 61 to lose its energy and, hence, shorten the life thereof.

The operation of the device, to maintain a correct temperature in each compartment of the incubator is effected as follows: Door 5 is normally closed, however, should the temperature within the compartment rise above the desired or predetermined degree, the excess heat would be allowed to escape by way of door or heat spiller 5. In this event, thermostat 61 would expand and depress lever 56, which would pull, in turn, rod 52 downward. Rod 52 would, therefore, exert a pressure on the end of rod 50 to rock member 42, and, thereby, elevate the

free end of rod 40. The horizontal or extended part 53 of rod 52 will increase the amount of leverage, whereby rod 40 will respond upon a very slight vertical motion of rod 52. The elevation of the free end of rod 40 will force antifriction roller 31 and bracket 15 to which it is connected upward, and, thereby, open door or heat spiller 5 by turning the same on its trunnions 6, 6. Immediately, the temperature within said compartment has fallen, the thermostat 61 will react to allow the free end of levers 56 and 50 to swing upward and likewise rock member 42 and rod 40 to swing downward. Weight 28 on door 5 would cause then said door 5 to return to closed position. Variations in the temperature within the compartment of the incubator will have their corresponding effect upon thermostat 61 which will react to control the movements of door 5. The degree of opening of door 5 can be controlled by regulating the adjusting screw 26.

Fig. 8 shows a modification. Here door 70 which corresponds to door 5 of the former construction is hinged at 71, 71 along its bottom edge rather than in its center part as is the case of door 5. A shoulder or reduced part 72 is formed on three sides of edges of door 70, whereby to make an air tight fit with its frame, when in closed position. Weight 75 is mounted on a U shaped rod 76 that is attached to door 70 by screw bolts 77, 77. Said weight 70 is suspended much higher up with relation to door 70 than weight 28 of door 5, in order to elevate the center of gravity and, thereby, aid said weight 75 in closing door 70.

Having thus described my invention what I claim as new and desire to secure by Letters Patent is:

1. In a heat spiller for incubators, a door adapted to open for the exit of hot air from said incubator, thermostatic means for controlling the movements of said door, and yielding means connecting said thermostat with said door to aid in prolonging the life of said thermostat.

2. In a heat spiller for incubators, a door mounted to the wall of said incubator, a thermostat for controlling the movements of said door, yielding means connecting said thermostat with said door, and a screw bolt for regulating the degree of opening of said door.

3. In a heat spiller for incubators, a door mounted to swing relative to said incubator, a thermostat for controlling the movements of said door, yielding means connecting said thermostat with said door, and means for regulating the degree of opening of said door.

4. In a heat spiller for incubators, a door mounted to swing, whereby to allow for the escape of hot air from said incubator, means

- attached to said door to aid in opening the same, a thermostat located within said incubator, a rod adapted to be actuated by said thermostat, yielding means connecting said rod with the thermostat, and said rod adapted to make contact with the means attached to said door, whereby to control the movements of said door.
5. In a heat spiller for incubators, a door mounted to swing, whereby to allow for the escape of hot air from said incubator, means attached to said door to aid in opening the same, a thermostat located within said incubator, a rod adapted to be actuated by said thermostat, said rod adapted to make contact with the means attached to said door, whereby to control the movements of said door, means for governing the degree of opening of said door and yielding means connecting said rod with said thermostat to aid in prolonging the life of the thermostat.
10. In a heat spiller for incubators, a door mounted to swing, whereby to allow for the escape of hot air from said incubator, means attached to said door to aid in opening the same, a thermostat located within said incubator, a rod adapted to be actuated by said thermostat, said rod adapted to make contact with the means attached to said door, whereby to control the movements of said door, means for controlling the degree of movement of said rod and yielding means connecting said rod with said thermostat to aid in prolonging the life of the thermostat.
15. In a heat spiller for incubators, a door mounted to swing, whereby to allow for the escape of hot air from said incubator, means attached to said door to aid in opening the same, a thermostat located within said incubator, a rod adapted to be actuated by said thermostat, said rod adapted to make contact with the means attached to said door, whereby to control the movements of said door, means for governing the degree of opening of said door and yielding means connecting said rod with said thermostat to aid in prolonging the life of the thermostat.
20. In a heat spiller for incubators, a door mounted to swing, whereby to allow for the escape of hot air from said incubator, means attached to said door to aid in opening the same, a thermostat located within said incubator, a rod adapted to be actuated by said thermostat, said rod adapted to make contact with the means attached to said door, whereby to control the movements of said door, means for controlling the degree of movement of said rod and yielding means connecting said rod with said thermostat to aid in prolonging the life of the thermostat.
25. In a heat spiller for incubators, a door mounted to swing, whereby to allow for the escape of hot air from said incubator, means attached to said door to aid in opening the same, a thermostat located within said incubator, a rod adapted to be actuated by said thermostat, said rod adapted to make contact with the means attached to said door, whereby to control the movements of said door, means for controlling the degree of movement of said rod and yielding means connecting said rod with said thermostat to aid in prolonging the life of the thermostat.
30. In a heat spiller for incubators, a door mounted to swing, whereby to allow for the escape of hot air from said incubator, means attached to said door to aid in opening the same, a thermostat located within said incubator, a rod adapted to be actuated by said thermostat, said rod adapted to make contact with the means attached to said door, whereby to control the movements of said door, means for controlling the degree of movement of said rod and yielding means connecting said rod with said thermostat to aid in prolonging the life of the thermostat.
35. In a heat spiller for incubators, a door mounted to swing, whereby to allow for the escape of hot air from said incubator, means attached to said door to aid in opening the same, a thermostat located within said incubator, a rod adapted to be actuated by said thermostat, said rod adapted to make contact with the means attached to said door, whereby to control the movements of said door, means for controlling the degree of movement of said rod and yielding means connecting said rod with said thermostat to aid in prolonging the life of the thermostat.

In testimony whereof I have affixed my signature.

HENRY W. RICHARDSON.
